CLAIM

The ornamental design for an instant camera, as shown and described.

DESCRIPTION

FIG. 1 is a top, front and right side perspective view of an instant camera showing my new design;

FIG. 2 is a top, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a top, front and right side perspective view thereof with a lens barrel protruded.

The portions of the design shown in broken lines form no part of the claim.
